(57) CLAIM

The ornamental design for padded volleyball shorts, as shown.

DESCRIPTION

FIG. 1 is a perspective view of padded volleyball shorts showing my new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

The back side of the shorts and lower leg section of the shorts shown in broken lines are not part of the ornamental design as claimed.

The even length broken lines and the unshaded areas adjacent to those broken lines define portions and features of the padded volleyball shorts that form no part of the claimed design. The dash-dot-dot-dash broken lines define the bounds of the claimed design and form no part thereof.
